UNITED STATES PATENT OFFICE.

ALBERT JOHN, JR., OF CHICAGO, ILLINOIS.

SPRING SHADE-ROLLER.

No. 873,438.

Specification of Letters Patent.

Patented Dec. 10, 1907.

Application filed January 31, 1906. Serial No. 298,783.

To all whom it may concern:

Be it known that I, ALBERT JOHN, Jr., a citizen of the United States, residing at Chicago, county of Cook, State of Illinois, have invented a certain new and useful Improvement in Spring Shade-Rollers, and declare the following to be a full, clear, and exact description of the same, such as will enable others skilled in the art to which it pertains to make and use the same, reference being had to the accompanying drawings, which form a part of this specification.

My invention relates in general to window shades, and more particularly to spring rollers for window shades.

In spring shade rollers as usually constructed, the spring is wound up and placed under tension when the shade is drawn down. The repeated winding and unwinding of the springs in time destroys their tension and they are frequently broken by the torsion which they are subjected to. Considerable annoyance is experienced in the use of shades owing to their being torn from the rollers when unwound too far.

The primary object of my invention is to provide a spring shade roller in which the spring will be placed under tension by its longitudinal extension when the shade is unwound and will rewind the shade by its longitudinal contraction.

A further object of my invention is to provide means for limiting the unwinding of a window shade to prevent its being torn from its roller and for limiting the unwinding of the shade.

A further object of my invention is to provide means for conveniently and securely fastening a shade to its roller.

A further object of my invention is to provide a roller which may be varied in length to fit windows of slightly different widths.

A further object of my invention is to provide an improved spring detent for permitting the shade to be wound up when the roller rotates rapidly but which, when the shade is permitted to wind slowly, will lock the roller against rotation by its spring.

The embodiment of my invention herein disclosed comprises a hollow roller formed of two longitudinal portions united by a dove-tail joint, an apron to which the shade is secured surrounding the roller and having one end interposed in the dove-tail joint, a coiled spring within the roller secured at one end to one end of the roller and at its other

end to a nut mounted to move longitudinally within but to rotate with the roller, a spiral grooved rod extending through and engaging a thread in the nut, one end of the rod projecting beyond an end of the roller and adapted to engage a bearing in a bracket thereby supporting the adjacent end of the roller and retaining the rod against rotation, an obstruction projecting into the path of movement of the nut to limit its movement and thereby limit the unwinding of the shade, a spring detent fixed to the projecting end of the rod and having a boss adapted to engage any one of a series of holes in the adjacent end of the roller, the other end of the roller being axially extensible to vary the length of the roller and having a pin 60 rotatably engage the supporting bracket.

My invention will be more fully described hereinafter with reference to the accompanying drawing in which the same is illustrated as embodied in a convenient and practical form, and in which,

Figure 1 is a sectional longitudinal section, 75 the shade being broken; Fig. 2 an end view of the roller looking from the left in Fig. 1; Fig. 3 an enlarged sectional view through the roller.

The same reference characters are used 80 to designate the same parts in the several figures of the drawing.

Reference character A indicates a shade roller formed in two longitudinal portions A' A² united by a dove-tail joint comprising 85 the wedge-shaped ribs a², a² on the portion A² and the co-operating wedge-shaped ribs a', a' on the other portion A' of the roller.

B indicates an axially extensible portion 90 of the roller provided with a pintle E' 95 adapted to engage a supporting bracket, and being reduced to fit within the hollow interior of the adjacent portion of the roller. Saw cuts may be conveniently formed in that part of the portion B' which extends within 100 the hollow adjacent portion of the roller to produce a frictional engagement.

B² indicates a cap located on the opposite end of the roller from the portion B' and provided with an inwardly projecting tube 105 B³ extending concentrically within the roller.

E indicates a rod having a spiral thread 110 in its exterior periphery and extending longitudinally within the roller. The inner end of the rod is supported within a socket formed in the portion B' of the roller while its opposite end extends through the tube

B³ and is provided with an angular or flattened projection E² adapted to engage a stationary bracket to support the adjacent end of the roller and also to hold the rod 5 against rotation. In order that the rod may be held axially immovable relatively to the roller but so as to permit the roller to rotate about the rod, a groove e² is formed in the portion of the rod E within the tube B³ 10 while pins such as b³ carried by the tube B³ lie within such tube.

H indicates a nut having a screw-threaded central opening through which the rod E extends. The nut H is provided with a 15 peripheral flange of a diameter slightly less than the interior diameter of the roller. A notch h is provided in such flange through which extends a rib a formed on the portion A² of the roller and projecting inwardly.

G indicates a coiled spring surrounding the rod E and having one end g extending through and rigidly secured to the end cap 20 B² of the roller. The other end of the spring g' is secured to the flange of the nut H. A screw or other obstruction K extends 25 into the path of movement of the nut H at any desired point.

F indicates a resilient detent fixed to the portion E² of the rod E in any suitable 30 manner such for instance as by means of a flange f closely surrounding the rod, the rod and surrounding flange being of such shape that a detent is prevented from rotation relatively with the rod. The free end of the 35 spring detent F is provided with a boss or other projection f' adapted to engage any one of a series of recesses b in the end cap E² of the roller.

C indicates an apron made of any suitable 40 fabric which surrounds the roller and is preferably secured thereto at its edge by means of a portion c being interposed between the ribs forming the dove-tail joint between the two portions of the roller as 45 clearly shown in Fig. 3. The apron may be glued or otherwise secured around the roller. The shade D may be secured in any suitable manner, such for instance as by sewing to the apron C. The portion C' of the apron 50 which extends around the extensible sleeve b² is made separate so that as the end portion B' of the roller is adjusted axially the portion of the apron C' will move therewith.

The operation of my invention is as follows: The shade D is secured around the roller A by means of the apron C. The shade is then wound up on the roller by hand in the usual manner after which the pintle E' and protecting end E² of the rod are located 55 in the supporting brackets. The shade is then unwound by drawing the lower end downwardly which rotates the roller around the rod E so that the nut H which rotates with the roller is fed along the rod inwardly. 60

65 The screw K or other obstruction is located

at such point that when the shade has been unwound the desired extent, it will be engaged by the flange of the nut H and thereby prevent further movement of the nut and further unrolling of the curtain and avoid any danger of the curtain being torn from the roller. When the curtain has been unwound the desired extent it is moved slowly so as to permit the boss f' on the spring detent F to engage one of the holes b and thereby retain the curtain unwound to the desired extent. In order to rewind the curtain it is given a quick movement downward which removes the boss on the detent from the edged recesses and by then allowing the curtain to move rapidly the detent is prevented from engagement with any of the recesses. It will be observed that the shade is also prevented from being rewound too far as the spring when it has contracted sufficiently to rewind the shade will contract no further.

From the foregoing description it will be observed that I have invented an improved spring roller for window shades in which the spring is placed under tension by axial extension, in which the shade is prevented from being torn from the roller, in which a convenient and secure means is provided for securing the shade to the roller, and which may be extended axially to adjust the same to windows of slightly different width.

Having now fully described my invention, what I claim as new, and desire to secure by Letters Patent is:

1. The combination with a hollow shade roller composed of two longitudinal portions united by a dove-tail joint and an axial adjustable end portion, of an apron having one section secured to said roller between the longitudinal portions and another section secured to the axial adjustable end portion, and a shade secured to said apron.

2. The combination with a spring shade roller, of an axial journal relatively to which said roller rotates, a resilient detent fixed at one end to said journal and a shoulder on the end of the roller for engaging with said detent and locking the roller against rotation or for permitting rotation of the roller according to the speed of rotation thereof.

3. The combination with a spring shade roller, of an axial journal relatively to which said roller rotates, a resilient detent fixed at one end to said journal, and a projection on said detent co-operating with recesses in the end of the roller to lock the roller against rotation or to permit the roller to rotate according to the speed of rotation of the roller.

4. The combination with a shade roller, of a window shade secured thereto, a coiled spring within said roller one end of which is secured to the roller, and means located within and rotating with the roller for expanding said spring longitudinally when the shade is

unwound thereby placing the spring under tension to rewind the shade.

5. The combination with a shade roller, of a window shade secured thereto, a coiled spring within said roller one end of which is secured to the roller, a block mounted within and rotating with said roller to which the other end of said spring is secured, and means for moving said block axially within the 10 roller when the shade is unwound thereby placing the spring under tension by expanding the same longitudinally to rewind the shade.

6. The combination with a shade roller, 15 of a window shade secured thereto, a coiled spring within said roller one end of which is secured to the roller, a block mounted within and rotating with said roller to which the other end of said spring is secured, means for 20 moving said block axially within the roller when the shade is unwound thereby placing the spring under tension by longitudinally expanding the same to rewind the shade, and a stop projecting into the path of movement of said block to limit its axial movement thereby limiting the unwinding of the 25 shade,

7. The combination with a shade roller, of a window shade secured thereto, a coiled spring within said roller one end of which is 30 secured to the roller, a non-rotatable rod extending concentrically within said roller and having a spiral groove therein, and a nut located within said roller to rotate therewith surrounding and in screw-threaded engagement with said rod, the opposite end of said spring being secured to said nut.

8. The combination with a shade roller, of a window shade secured thereto, a coiled spring within said roller one end of which is 40 secured to the roller, a non-rotatable rod extending concentrically within said roller and having a spiral groove therein, a nut surrounding and in screw-threaded engagement with said rod, the opposite end of said spring being secured to said nut, and a spring 45 detent fixed to said rod co-operating with said roller to lock the same against rotation.

In testimony whereof, I sign this specification in the presence of two witnesses.

ALBERT JOHN, JR.
